CLAIM

The ornamental design for a sensor for measuring shaft rotation, as shown and described.

DESCRIPTION

FIG. 1 is a front perspective view of a sensor device illustrating my new design;

FIG. 2 is a front view of the design of FIG. 1;

FIG. 3 is a rear view of the design of FIG. 1;

FIG. 4 is a side view of the design of FIG. 1;

FIG. 5 is a side view of the design of FIG. 1;

FIG. 6 is a side view of the design of FIG. 1;

FIG. 7 is a side view of the design of FIG. 1; and,

FIG. 8 is a perspective view of the design of FIG. 1 in use on a shaft.

The broken lines represent environmental structure that forms no part of the claim.
